UNITED STATES PATENT OFFICE.

DONALD C. WATSON, OF WESTON, MASSACHUSETTS, ASSIGNOR TO UNIVERSAL BORING MACHINE COMPANY, OF HUDSON, MASSACHUSETTS, A CORPORATION OF MASSACHUSETTS.

DESIGN FOR A LEVEL.

59,943.

Specification for Design.

Patented Dec. 6, 1921.

Application filed July 5, 1921. Serial No. 482,604. Term of patent 3½ years.

To all whom it may concern:

Be it known that I, DONALD C. WATSON, a citizen of the United States, residing at Weston, in the county of Middlesex and State of Massachusetts, have invented a new, original, and ornamental Design for a Level, of which the following is a specification, reference being had to the accompanying drawing, forming a part hereof.

The single figure of the drawing is a perspective view of a level showing my new design.

I claim:

The ornamental design for a level, as shown.

DONALD C. WATSON.
